UNITED STATES PATENT OFFICE

GEORGE BOULTON, OF ROCHESTER, NEW YORK, ASSIGNOR TO UNITED SHOE MACHINERY CORPORATION, OF PATERSON, NEW JERSEY, A CORPORATION OF NEW JERSEY

SEAM PRESSING MACHINE

Application filed June 1, 1927. Serial No. 195,702.

This invention relates to seam pressing machines and is herein illustrated as embodied in a seam ironing machine of the type disclosed in United States Letters Patent No. 5 1,342,417, granted June 8, 1930, upon application of Boulton and Gorsuch.

In the machine shown in the Letters Patent referred to a plow yieldingly mounted above a stationary work supporting saddle is 10 adapted to open a seam in a piece of work, and a heated pressing member or ironing block is arranged to cooperate with a power-driven work supporting feed roll to press and iron the seam after it has been opened 15 by the plow. In the operation of this machine one end of a piece of work is fed manually until it has passed beyond the plow and has advanced at least some distance between the ironing block and the feed roll, after 20 which the feed roll functions to continue the feed of the work under power.

In accordance with one feature of the present invention, the illustrated machine is provided with means for cooperating with a 25 work support, a feed roll as herein embodied, at a point between a plow and a seam pressing member or ironing block to facilitate the feeding of the work. As herein shown, this means consists of a yieldingly mounted roller 30 presser foot comprising two idle rollers having beveled peripheries arranged to co-operate with beveled peripheral faces at opposite sides of that portion of the periphery of the work supporting feed roll which 35 operates with the ironing block. This roller presser foot relieves the operator of the necessity of continuing the feed of the work manually after it leaves the plow while still permitting the operator manually to control 40 the presentation of the leading end of the seam to the plow. The roller presser foot is so mounted that it may readily be removed to adapt the machine for operation upon certain classes of work where it may be found 45 desirable to prolong the period during which the feed of the work is manually effected, and consequently advantageous to dispense with the presser foot.

Among the many classes of work for which 50 machines of the type above referred to are

adapted is the pressing of seams of cloth caps for which purpose such machines are now used quite extensively. In pressing the seams of caps it is the practice to start at the rim of the cap and to feed the cap so that the seam is pressed progressively toward the center of the cap and often it is desirable to stop the feed when the center of the cap reaches the pressing member and to remove the work by backing it out from beneath the pressing member. 55

In view of the foregoing, and in accordance with another feature of the present invention, provision is made in the illustrated machine for facilitating the removal or "backing out" 60 of the work from the machine in the manner above referred to without opening up the pressed seam or disturbing it in any way. To this end, as illustrated, means is constructed and arranged to be actuated by the 65 pressing member or ironing block as the latter is retracted from cooperative relation with the work supporting roll to retract seam guiding fingers so that they will not have any tendency to open up or disturb the seam. As 70 shown, this means comprises an extension protruding from the plow into the path of movement of the ironing block. The arrangement, therefore, is such that the plow as well as the seam guiding fingers is re- 75 tracted, thus still further facilitating the removal of the work from the machine. 80

When a roller presser foot, such as that above referred to, is employed to co-operate with a work supporting roll in the feeding 85 of the work it is desirable, in order to enable the work to be "backed out" as above described, and sometimes also in order to facilitate the introduction of the work or the temporary stopping of the feed, that provision 90 should be made for retracting the presser foot when the ironing block and the plow are retracted. Accordingly, a still further feature of the invention consists in the provision of means for utilizing the retracting movement of the ironing block to retract also the 95 presser foot as well as the seam guiding fingers and the plow.

The invention further comprises an improved ironing block especially adapted for 100

operation upon double-stitched seams, an improved means for supporting the portion of the work which is being acted upon by the plow, such means being constituted in the illustrated embodiment of the invention by a stationary work rest designed particularly to adapt the machine for operating upon the seams of caps. It is customary in the operation of seam pressing machines to impart a slight tension to the work transversely of the seam to insure that wrinkles will not be pressed into the material in the vicinity of the seam. In accordance with the above, another feature of the invention comprises a work rest having work supporting surfaces which slope downwardly at either side of the seam pressing means and a rib to facilitate guiding the work to the pressing means. As a result of such a construction the operator's hands, usually placed on the work at each side of the pressing means to guide the work and supported in the illustrated machine on the sloping sides of the work rest, tend to slide downwardly and hence tension the work sufficiently transversely of the seam to remove whatever wrinkles might otherwise remain and become impressed in the work by the operation of the pressing means.

Other novel features and combinations of parts will now be set forth in the following description and defined in the appended claims.

The invention will be explained with reference to the accompanying drawings, in which, Fig. 1 is a fragmentary view, partially in elevation and partially in section, of a machine embodying the features of the present invention;

Fig. 2 is a detail view, in front elevation and on an enlarged scale, of certain of the operating parts of the machine;

Fig. 3 is a detailed elevational view of the portion of the machine shown in Fig. 2, illustrating particularly the manner which the parts operate upon the work;

Fig. 4 is a perspective view showing a double-stitched seam as it appears when being presented to the action of the plow;

Fig. 5 is a detailed view, partially in section on the line V—V of Fig. 7, illustrating the mode of operation of the ironing block upon a double-stitched seam;

Fig. 6 is a perspective view further illustrating the co-action of the ironing block and the work supporting roll upon a double-stitched seam;

Fig. 7 is an end elevational view, on an enlarged scale, of the operating parts shown in Fig. 1, and

Figs. 8 and 9 are plan and side elevational views, respectively, of a stationary work rest particularly adapting the machine for cap work.

The seam pressing machine shown in the drawings is provided with a work-support-

ing feed roll 12, a stationary work rest 14 which is arranged to cover portions of the feed roll and to support the work as it is being presented to the machine, a seam-opening plow 16, a pair of seam guiding members 18, 18, and a heated presser member or ironing block 20. The feed roll is driven from a pulley shaft (not shown) through connections including intermeshing bevel gears 22 (Fig. 1). The plow 16 is carried by a vertical rod 24 which is slidable in guideways formed in lugs 26, 28 projecting from the frame of the machine. A spring 30, surrounding the rod 24 between the lug 26 and a collar 32 fixed on the rod, urges the plow downwardly and tends to hold it in a position determined by an adjusting nut 36 arranged to engage the lug 26 and held in place by means of a check nut 38. The seam guiding members 18, 18 comprise thin resilient fingers the upper ends of which are fixedly secured to the upper portion of the plow 16. The lower ends of the seam guiding fingers are turned inwardly and shaped to engage the seam margins throughout only relatively small portions of the widths of the margins so as not to retard the feed of the work. The fingers 18 are adapted to be independently adjusted inwardly and outwardly by means of adjusting screws 40, 40 which are threaded through the fingers and engage opposite sides of the plow. Friction springs 42, 42 surrounding the shanks of the adjusting screws 40 and arranged to bear against the heads thereof serve to maintain the screws in adjusted position.

The ironing block 20 is secured to a carrier 44 which is urged toward the feed roll by means of a spring 46 and the carrier is supported for yielding sliding movement against the force of the spring by means of adjustable guide plates 48, 48 and a guide block 50 which is pivoted to the frame of the machine and is received in a slot 52 in the ironing block carrier 44. The approach of the ironing block relatively to the feed roll 12 is limited by a screw 54 which extends through the coils of the spring 46 and is threaded through a portion of the carrier 44, the inner end of the screw bearing against the pivoted guide block 50. A screw 55 backs up the spring 46 and may be turned to vary its tension. The ironing block 20 is adapted to be moved away from the feed roll to facilitate either the insertion or removal of the work, or for the purpose of stopping the feed of the work, by means of an arm 56 fast on a rockshaft 58 and extending into a recess in the carrier 44. The rockshaft 58 is connected by means of an arm 60 and a rod 62 with a foot treadle (not shown) by means of which the arm 56 may be operated to raise or lower the ironing block.

Except in certain respects hereinafter specifically pointed out, the construction and

arrangement of the parts thus far described is substantially the same as that of corresponding parts shown and described in Letters Patent No. 1,342,417, hereinbefore referred to.

In the illustrated machine, in order to insure that the work may be fed under power as soon as the seam passes beyond the seam guiding fingers 18, means is provided, illustrated as a roller presser foot 66, for co-operating with the work supporting feed roll 12 at a point between the plow and the ironing block, this arrangement rendering it unnecessary for the operator to continue the manual feed of the work after the work has passed beyond the plow, thus effecting a substantial saving of time, particularly when operating upon work having short seams.

The presser foot 66 (Figs. 2 and 7) comprises a yoke-shaped member having rearwardly curved arms arranged to straddle the plow and the seam guiding fingers and carrying at the lower end of each of its arms a freely rotatable roller 68. The peripheries of the rollers 68 are beveled and knurled, as shown, to engage correspondingly beveled and knurled faces 70, 70 at opposite sides of the feed roll 12. The presser foot 66 is secured to the lower end of a vertical rod 72 mounted for yielding sliding movement in guideways formed one in an extension of the lug 26 and the other in a lug 74 and the presser foot 66 is urged downwardly and adapted to be held in yielding engagement with the work by means of a spring 76 encircling the rod 72 between the lug 26 and a collar 78 adjustably fixed on the rod. A nut 80 threaded on the upper end of the rod 72 and adapted to be held in position by a check nut 82 is arranged to engage the lug 26 to limit the downward movement of the presser foot when the latter is raised, as will be hereinafter described. By unscrewing the nuts 80 and 82 the presser foot may be removed from the machine in case it is desired to adapt the machine for operation upon certain classes of work in which the supplementary feeding action, caused by the presser foot when it is arranged to urge the work against the feed roll 12, is not advantageous.

In the illustrated machine, for the purpose of raising the seam-guiding fingers and the plow so as to facilitate the backing of the work out of the machine, connections between the plow and the ironing tool 20 are provided in the form of an arm 84 (Fig. 7) projecting rearwardly from the upper portion of the plow and carrying an adjustable abutment screw 86 held in position by means of a check nut 88 and adapted to be engaged by a shoulder 90 on the ironing block when the latter is raised by the operator. By means of the above-described connections upward movement of the ironing block is transmitted to the plow, and to the seam guiding

fingers which are carried by the plow, thus raising both the plow and the fingers out of the path of the seam. The screw 86 may be adjusted to vary the extent to which the plow and the seam guiding fingers will be raised or to enable the ironing block to be raised without also raising the plow and the seam guiding fingers.

When the above-described roller presser foot is employed it is desirable that means be provided for lifting it out of cooperative relation with the feed roll 12 to facilitate removal of the work by backing the work out of the machine.

To this end, as best shown in Fig. 7, a pin 80 projects from the collar 78 and overlies the collar 32 on the rod 24 which carries the plow. With this arrangement, when the rod 24 is moved to raise the plow and seam guiding fingers the movement of the rod 24 is transmitted to the rod 72, thus causing the presser foot to be raised also.

To facilitate operating upon certain classes of work, particularly work having a double-stitched seam, such as that shown in Figs. 3 and 4, in order to insure that the outer edges of the margins united by the seam will be properly pressed and in order to provide for the application of a more uniform pressure throughout the entire width of each of the seam margins, the seam ironing block 20 is herein shown (see Figs. 5 and 6) as being recessed at 94 so as to relieve the ironing pressure somewhat immediately over the line of stitching. As a result of thus recessing the ironing tool not only is there insured a more uniform application of pressure upon the seam margins but the ironing block has practically no tendency to break the outermost stitches of the seam.

The stationary work rest 14 of the illustrated machine is especially designed to adapt the machine for operating upon the seams of caps. For this purpose, the rest 14, as shown in Figs. 1, 8 and 9, is of a generally semi-spherical outside contour, particularly adapted to extend within and support a substantial portion of the inside of a cap so that after completing the pressing of any of its seams the cap may be more readily turned to position another seam to be operated upon. As shown, the spherical work rest 14 is formed with a web portion 96 adapted to be secured by screws such as 97 (Fig. 1) to the frame of the machine. The rest 14 is cut away as indicated at 98 to avoid interference with the roller presser foot. An upstanding rib or fin 100 upon the upper surface of the rest 14 is arranged immediately beneath the plow and is arranged to enter the crease of the seam upon the display side of the work to facilitate the guiding of the seam. Not only does the above-described improved work rest 14 facilitate the presentation of the work to the operating tools as above described, but it also

enables an operator the better to control the seam as it is being passed through the machine. The improved rest also has the advantage of covering the feed wheel in such a manner as to eliminate any danger of oil or grease from the feed roll bearings reaching the work.

In operation the work is placed, display side down, on the work rest 14 so that the rib 100 enters the crease of the seam and the upstanding margins of the seam are directed between the inturned lower ends of the seam guiding fingers 18. As the work is manually fed over the work rest the plow 16 functions, as in the machine disclosed in the Letters Patent above mentioned, to open the seam and to lay the seam margins over against the surface of the work in position to be ironed flat by the ironing block 20. Before reaching the ironing block, however, and immediately after passing beyond the plow the work passes between the presser foot 66 and the beveled faces of the feed roll 12 and is fed under power to the ironing block. Inasmuch as the roller presser foot is so positioned as to be effective at a point between the plow and the ironing block, its action in no way interferes with the manual control of the work as the seam is directed between the seam guiding fingers and is entered beneath the plow, but the presser foot functions as soon as the seam has left the plow, and before the seam has traversed the clearance space between the plow and the ironing block, to feed the work forwardly under power, thus relieving the operator of the necessity of continuing the feed of the work manually until it has advanced a substantial distance beneath the ironing block. Although the distance through which the work is fed solely by the cooperation of the roller presser foot and the feed roll is not very great, it is nevertheless a very substantial portion of the full distance traveled by the work when short seams are being operated upon. Consequently, it will be appreciated that a very substantial saving in time is effected as a result of the provision of the presser foot. Furthermore, the provision of two presser rolls on the presser foot arranged as herein described insures that the work will be fed uniformly at both sides of the seam and thus maintained automatically in a straight path. The operator is thus practically relieved of the necessity of manually guiding the work after it has passed the presser foot and danger of stretching the seam in the act of manually guiding it is eliminated. As the seam passes beneath the ironing block the depression 94 receives the bulge of the seam along the line of stitching, relieving the pressure at this point sufficiently to insure that the edges of the seam margins will be properly pressed. If the work being operated upon is a cap the spherical shape of the work support 14 facil-

itates manipulation of the cap after each seam thereof has been pressed so that the cap may be repositioned for the pressing of the next seam with a minimum amount of effort. As hereinbefore mentioned, the roller presser foot may be readily removed if its use is not desired when operating upon the seams of caps. If for any reason it is desirable to back the work out of the machine after a seam has been ironed, the operator through the treadle connections herein described may not only raise the ironing block but he may also, and by the same operation raise the seam guiding fingers, the plow and the presser foot thus releasing the work so that its removal may be readily and easily accomplished.

Having thus described my invention, what I claim as new and desire to secure by Letters Patent of the United States is:—

1. In a seam pressing machine, a work supporting feed roll, a seam opening plow, a seam pressing member arranged to cooperate with the feed roll in the pressing of a seam, and yielding means for cooperating with the feed roll at a point between the plow and the pressing member to facilitate the feed of the work.

2. In a seam pressing machine, a work supporting feed roll, a seam opening plow, a seam pressing member arranged to cooperate with the feed roll in the pressing of a seam, and a yieldable roller presser foot arranged to cooperate with the feed roll between the plow and the presser member to feed the work beneath the presser member.

3. In a seam pressing machine, a work support, a presser foot arranged to cooperate with the support to feed the work, a slidably seam pressing member yieldingly urged toward the work support, a seam opening plow, means for guiding a seam to the plow, and means carried by the plow and projecting into the path of movement of the seam pressing member for transmitting the movement of the seam pressing member to the plow and seam guiding means.

4. In a seam pressing machine, a work supporting feed roll, a seam pressing member movable toward and from position to co-operate with the feed roll to press a seam, a seam opening plow capable of being retracted from operative position, seam guiding fingers connected with the plow, a roller presser foot for co-operating with the feed roll in the feeding of the work, and means controlled by a single operating member for retracting the seam pressing member, the plow, the seam guiding means, and the presser foot.

5. In a seam pressing machine, a work supporting feed roll, a seam pressing member movable toward and from position to co-operate with the feed roll to press a seam, a seam opening plow capable of being retracted from operative position, seam guiding fingers connected with the plow, a roller presser

- foot for co-operating with the feed roll in the feeding of the work, means for retracting the presser member, means carried by the presser foot and plow in the path of movement of the plow and the presser member respectively whereby the plow and presser foot are successively relieved as the presser member is retracted. 5
6. In a seam ironing machine, a work supporting and feeding roll, a presser foot arranged to cooperate therewith to assist in feeding the work, a heated ironing block provided with a curved work contacting face disposed adjacent to the work supporting roll for a considerable portion of the periphery thereof, a treadle operated member, connections between said member and the ironing block for causing the latter to be retracted from operative relation to the work supporting roll, a seam opening plow capable of being raised and lowered, and means connected with the plow and extending into the path of movement of the ironing block whereby the plow is raised when the ironing block is retracted. 10
7. In a seam pressing machine, a seam pressing member, a roller presser foot, a work supporting roll with which the seam pressing member and the presser foot co-operate to feed the work, and operator-controlled means for retracting both the seam pressing member and the presser foot from the work supporting roll. 15
8. In a seam pressing machine, a seam pressing member, a roller presser foot, a work supporting roll with which the seam pressing member and the presser foot co-operate to feed the work, a seam opening plow arranged above the work supporting roll, and means for retracting both the seam pressing member and the presser foot from the work supporting roll and for raising the plow. 20
9. In a seam pressing machine, a stationary work rest, a seam opening plow arranged above the rest, means for guiding the seam to the plow, a work supporting feed roll, a presser member arranged to co-operate with the feed roll to press and feed the work, and means for retracting the plow and the seam guiding device from the rest and for simultaneously retracting the seam pressing member from the feed roll. 25
10. In a seam pressing machine, a work supporting feed roll, a seam pressing member movable toward and from the feed roll, a work supporting saddle, a seam opening plow located above the saddle and capable of being raised and lowered, a presser foot arranged to co-operate with the feed roll at a point between the plow and the pressing member to feed the work to the latter, means connected with the plow arranged to be actuated by the seam pressing member to raise the plow when said member is retracted, and means in the path of movement of the plow and carried by the presser foot for raising the presser foot in unison with the plow. 30
11. In a seam pressing machine, seam pressing means, means for supporting the work in operative relation to the pressing means and for cooperating with the pressing means to feed the work, a work rest comprising downwardly sloping work engaging surfaces disposed one at either side of the seam pressing means, and a rib on said rest to facilitate the guiding of the work by contact with the seam. 35
12. In a seam pressing machine, seam pressing means, means for supporting the work in operative relation to the pressing means and for cooperating with the pressing means to feed the work, a work rest having a surface sloping downwardly in all directions from the seam pressing means, and a rib on said rest to facilitate the guiding of the work by contact with the seam. 40
13. In a seam pressing machine, seam pressing means, means for supporting work in operative relation to the seam pressing means and cooperating therewith to feed the work, and a stationary work rest having a curved surface sloping downwardly at either side of the seam pressing means. 45
14. In a seam pressing machine, seam opening and pressing means, means for supporting a piece of work to position a seam in operative relation to the opening and pressing means, and a stationary work rest arranged to expose a portion of the work supporting means adjacent to the seam opening and pressing means, the work engaging surface of said work rest being convexly curved and sloping downwardly in all directions from the seam pressing means. 50
- In testimony whereof I have signed my name to this specification. 55
